United States Patent Office

Des. 189,056

Patented Oct. 18, 1960

189,056

MATCH BOX COVER

Peter A. Parker, 145 Nash St., Rocky Mount, N.C.

Filed Oct. 26, 1959, Ser. No. 58,052

Term of patent 14 years

(Cl. D48—29)

Fig.1

Fig.2

I claim:

The ornamental design for a match box cover, as shown.
